UNITED STATES PATENT OFFICE.

JOHN H. GOSS, OF WATERBURY, CONNECTICUT, ASSIGNOR TO THE SCOVILL MANUFACTURING COMPANY, OF SAME PLACE.

BICYCLE-BELL.

SPECIFICATION forming part of Letters Patent No. 625,672, dated May 23, 1899.

Application filed November 7, 1898. Serial No. 695,763. (No model.)

To all whom it may concern:

Be it known that I, JOHN H. GOSS, a citizen of the United States, residing at Waterbury, in the county of New Haven and State of Connecticut, have invented a certain new and useful Improvement in Bicycle-Bells, of which the following is a full, clear, and exact description.

The object of this invention is to provide an antirattling device for bells of that class in which the bell-hammer is actuated by a vibrating lever having a toothed segment which operates a train of gearing connected with the hammer.

The invention consists of a bell-lever having a toothed segment pivoted thereto for operating a train of gearing, the lever itself preferably having one or more teeth to coöperate with the teeth of the segment and with the gear mechanism to lock or hold the mechanism when out of operation—that is to say, during the time when the bell is not being sounded.

In the accompanying drawings illustrating my invention, in the several views of which like parts are similarly designated, Figure 1 is a horizontal section taken immediately below the bell-hammer. Fig. 2 is a perspective view of the vibrating lever. Fig. 3 is a plan view showing the bell-lever and segment combined and arranged in relation to the driving-gear pinion, the parts being at rest. Fig. 4 is a cross-section of the base of the bell with the actuating mechanism in elevation. Fig. 5 is a view similar to Fig. 3, showing the bell-lever and toothed segment at the end of the forward throw. Fig. 6 shows in two perspective views the pivotal toothed segment. Fig. 7 is a view similar to Fig. 4, but taken at about right angles to the last-named view.

The base *a*, the driving-gear *b*, its pinion *c*, the post *d*, the hammer-pinion *e*, and the bell-lever spring *f* may be of substantially usual construction.

The bell-lever *g* is pivoted at *h* to the base, and instead of being continued, as heretofore, to form a segment on its free arm *g'* said free arm terminates short and is provided with one or two teeth *g''*. To the end of the bell-lever is pivoted the toothed segment *i*, which

meshes with the pinion *c* in order to rotate the train of gearing which drives the hammer, and in order to adapt this pivoted toothed segment *i* to accomplish an antirattling function with relation to the actuating mechanism I make the end *i'* substantially wedge shape or tapering and provide it with a depending stop-lug *i''*, which comes into contact with the free arm of the bell-lever when the said lever has been manually impelled, as indicated in Fig. 5, to actuate the train of gearing and sound the bell, the said stop-lug *i''* thus preventing the undue inward movement of the said toothed segment and the unmeshing of the toothed segment and pinion under the influence of the leverage exerted on the pivot, and when the bell-lever and toothed segment are in the position of rest indicated by Figs. 1 and 3 and are so held by the spring *f* the device *i* becomes an antirattler by being wedged in between the pinion *c* and the hub of the pinion *e*, the teeth *g''* coöperating at this time with the teeth of the segment *i* and pinion *c*, as it were, to lock the parts. The said bell-lever may be given a slight rise throughout its free arm and from its pivotal point if the segment is not otherwise sufficiently elevated.

I provide the toothed segment with the lug *i''*, which coöperates with the stop-lug *i''* to support said toothed segment and the free end of the lever above the floor of the base. The lug *i''* not only holds up the end of the segment, but also serves to keep off the strain from the pivotal rivet, and, further, keeps the segment in a plane parallel with that of the bell-base, so that the teeth of the segment mesh with those of the pinion.

What I claim is—

1. In a bell, a vibrating spring bell-lever, having a short free end and a toothed segment pivoted upon the upper face of said lever and at its free end and adapted to be wedged or jammed in between any usual train of gearing for actuating the bell-hammer, and to operate said gearing, substantially as and for the purpose described. 90

2. In a bell, a vibrating spring bell-lever, and a toothed segment pivoted thereto and provided with a depending stop-lug which en- 95

gages said bell-lever to limit the vibration of said segment upon the said bell-lever, substantially as described.

3. In a bell, a vibrating spring bell-lever, having the end of its free arm provided with one or more teeth, and a toothed segment pivoted to the upper portion of such end of said bell-lever, its teeth registering with the teeth of the bell-lever, and a depending stop-lug on said segment engaging the bell-lever for limiting the vibration of the said toothed segment on the said bell-lever, substantially as described.

4. In a bell, a vibrating spring-lever, having its free arm rising from the pivotal point,

and a toothed segment pivoted to said free arm and provided with end lugs, substantially as and for the purpose described.

5. In a bell, a vibrating spring-lever, a toothed segment pivoted to the upper face thereof and a depending lug at the free end of said segment, substantially as and for the purpose described.

In testimony whereof I have hereunto set my hand this 3d day of November, A. D. 1898. 25

JOHN H. GOSS.
